US00D790962S

(12) **United States Design Patent** (10) **Patent No.:** **US D790,962 S**
(45) **Date of Patent:** **** Jul. 4, 2017**

(54) **DESICCANT PACKAGE**

(71) Applicant: **Ear Technology Corporation**, Johnson City, TN (US)

(72) Inventors: **Daniel R. Schumaier**, Elizabethton, TN (US); **Joseph S. Riner**, Johnson City, TN (US); **James L. Adkins**, Johnson City, TN (US)

(73) Assignee: **EAR TECHNOLOGY CORPORATION**, Johnson City, TN (US)

(**) Term: **15 Years**

(21) Appl. No.: **29/550,533**

(22) Filed: **Jan. 5, 2016**

(51) LOC (10) Cl. **09-03**

(52) U.S. Cl.

USPC **D9/416**; D9/425

(58) **Field of Classification Search**

(57) **CLAIM**

The ornamental design for a desiccant package, as shown and described.

DESCRIPTION

FIG. 1 is a bottom perspective view of a desiccant package; FIG. 2 is a top perspective view of the desiccant package; FIG. 3 is a front side elevation view of the desiccant package;

FIG. 4 is a rear side elevation view of the desiccant package; FIG. 5 is a right side elevation view of the desiccant package;

FIG. 6 is a left side elevation view of the desiccant package; FIG. 7 is a top plan view of the desiccant package;

FIG. 8 is a top plan view of the desiccant package with the lid removed; and,

FIG. 9 is a bottom plan view of the desiccant package. The broken lines shown represent unclaimed subject matter and form no part of the claimed design.

1 Claim, 6 Drawing Sheets
